DESIGN FOR A WOMAN'S WORK CAP

Joanna E. Higgins, Providence, R. I.

Application October 29, 1942, Serial No. 108,630

Term of patent 7 years

To all whom it may concern:

Be it known that I, Joanna E. Higgins, a citizen of the United States, residing at Providence, in the county of Providence and State of Rhode Island, have invented a new, original, and ornamental Design for a Woman's Work Cap, of which the following is a specification, reference being had to the accompanying drawing, forming a part thereof, in which

Fig. 1 is a view in perspective of a woman's work cap showing my new design as seen from the front,

Fig. 2 is a corresponding view of the cap as seen from the left side,

Fig. 3 is a corresponding view of the cap as seen from the right side, and

Fig. 4 is a corresponding view of the cap as seen from the rear.

I claim:

The ornamental design for a woman's work cap, substantially as shown and described.

JOANNA E. HIGGINS.
